TWO-UNIT WELTING

William C. Vizard, Brockton, Mass., assignor to
Barbour Welting Company, Brockton, Mass., a
co-partnership

Application November 29, 1945, Serial No. 631,576.

5 Claims. (Cl. 12—146)

1 This invention relates to two-unit welting of the heavy-edge type shown in the Lyon and Gilson Patent No. 1,708,628, dated April 9, 1929, and the principal purpose of the present invention is to provide a two-ply leather welt having a grain surface on the welt extension or deck, and a grain lip extending over a shoulder along the inner edge of the welt; the welt plies being cut from a leather strand or fillet in such a manner that the resulting product affords a deck surface appreciably wider than any heretofore produced from a fillet of a given width, and presents an undercut or receding shoulder disposed above the inseam flange and adapted to closely hug the shoe upper at or slightly below the level of the insole when the welt is built into a shoe channeled for ordinary Goodyear welting.

As the shoe manufacturer purchases welting according to the required width of the resultant welt extension or deck and not according to the overall width of the welt, it is apparent that welting which affords the desired deck surface yet may be produced from a narrower fillet, effects substantial economies in the manufacture of the welt, even when the saving of leather is not over $\frac{1}{8}$ inch. The method of making two-unit welting according to this invention, permits this saving primarily because of the formation of the grain lip and the undercut flesh wall which produces the receding shoulder and thereby ensures a closer fitting, non-grinning welt capable of holding the shoe upper in proper position and obviating the formation of a gutter between upper and welt.

Recommended embodiments of the invention are illustrated in the accompanying drawing, but it will be understood that the methods of manufacture and structural details of the embodiments herein disclosed may be varied to suit particular requirements without departing from the essence of the invention as defined in the appended claims. In the drawing,

Fig. 1 is a perspective view of a fillet partially divided longitudinally to produce the two units of the heavy welting;

Fig. 2 is a perspective view of the plied welt, made from the fillet of Fig. 1;

Fig. 3 is a view similar to Fig. 1, showing an optional modification in which the widths of the two units are approximately equal;

Fig. 4 is a fragmentary section through the toe portion of a shoe made with the welt of Fig. 2;

Figs. 5 and 6 are views similar to Figs. 1 and 2 showing a modification in the method of dividing the fillet and the resultant welt;

2 Figs. 7 and 8 are similar views of another modification; and

Figs. 9 and 10 are similar views illustrating a further modification of the division of the fillet, and the characteristics of the resulting product.

In each of the optional methods herein illustrated, a grain leather fillet, which may be of standard one-eighth inch thickness, is divided longitudinally by an inclined cut which forms an undercut wall in the flesh body, and a lateral or sloping incision adjacent the upper surface and at an obtuse angle to the first cut to form a thin grain lip or cover flap in the unit which is to constitute the top layer of the welt; the base unit is formed to provide a beveled or thinned inseam flange along one edge; the two layers are firmly cemented in superposed relation; and the cover flap is folded and cemented under pressure against the undercut flesh shoulder to produce the receding welt shoulder, and onto the surface of the inseam flange or, preferably, over its beveled edge to increase the width as well as the thickness of the flange, and to afford firm anchorage for the inseam stitch.

25 In Fig. 1 a fillet $\frac{1}{8}$ inch wide is divided to form a top unit 11 and a base unit 12, by a cut which enters the flesh base in a vertical direction, then inclines to form the undercut flesh wall 13, and finally slopes laterally to the edge of the fillet to provide a tapering grain lip 14 of the top unit. The base unit thus has a sloping upper surface 15 and an inseam edge which is beveled at 16. The bottom surface of the top unit, as shown, has a width of $\frac{1}{2}$ inch; and the bottom of the base unit is $\frac{1}{8}$ inch wide.

The two units are cemented together as shown in Fig. 2 with the cover flap 14 adhesively secured to the wall 13 and to the exposed surfaces of the base, to provide the receding welt shoulder 17 and the sturdy inseam flange 18. The finished welt presents a deck $1\frac{1}{2}$ inch wide, and has a base (including the thickness of the lip) a full half-inch in width.

45 This welt is built into a shoe, bottomed for ordinary Goodyear welting, as indicated in Fig. 4, the inseam flange being pulled tightly under the feather of insole 19 by the curved stitch 20 to secure the margin of the upper and lining against the channeled sewing lips of the insole, and to press the welt shoulder 17 against the upper near the top of the insole. When thus secured and stitched to the outsole, it is evident that the welt will hold the shoe in shape and will not spread away from the upper during ordinary wear of the shoe.

3

Fig. 3 shows a variation in the welt of Fig. 2, producing a full half-inch deck and a base $1\frac{1}{32}$ inch wide, made from the fillet of Fig. 1 by so placing the base cut that the bottom of the top unit 21 has a width of $1\frac{1}{32}$ inch, and the bottom 5 of the base unit 22 is $1\frac{1}{32}$ inch wide.

In the modification shown in Figs. 5 and 6, a 10 welt having a deck $1\frac{1}{32}$ inch wide and a full half inch base is produced from a fillet $2\frac{7}{32}$ inch wide by making a diagonal cut $1\frac{1}{32}$ inch from the left-hand edge of the fillet, as at 23, a lateral cut 24 terminating $\frac{3}{32}$ inch from the right-hand edge, and a short vertical cut to the grain surface, to 15 form units 25 and 26. Top unit 25 has the undercut flesh wall at 23, and a relatively narrow grain lip 27; and base unit 26 has a sloping inseam flange 28, and a narrow grain platform 29. The latter is preferably buffed or skived, before 20 the units are cemented together under molding pressure, as in Fig. 6. As before, the cover flap 27 is cemented to the undercut flesh wall and over the sloping surface of the inseam flange.

In the remaining modifications a wider fillet (approximately one inch) is employed to furnish a welt having a full half-inch deck and a relatively wide base, and the grain lip of the top unit is cemented to an undercut wall and onto the flat top surface of an inseam flange of the base unit, but does not extend over the edge to the bottom of the base unit. These variations accordingly do not afford the manufacturing economies of the previous examples, but provide a sturdier construction for heavier shoes.

The form shown in Figs. 7 and 8 provides an elevated inseam flange and is particularly advantageous for shoes made with receding toes, for the inseam flange may be trimmed flush, without severing the inseam stitch which passes through the crease at the bottom of the receding shoulder. The fillet is cut substantially as shown in Fig. 5, to provide the top unit 31 and base unit 32, but the base unit is inverted so that the flat flesh side is cemented to the top unit and its grain platform 33 is on the bottom, thereby furnishing the elevated inseam flange 34 which is covered by the grain lip 35 of the top unit. The inseam groove 36 is located at the angle between the platform and the body of the inverted base unit, and the inseam stitch is buried in this groove, remote from the bottom of the 50 welt and out of the way of the trimmer which guides on said bottom.

In Figs. 9 and 10, the fillet is also divided substantially as shown in Fig. 5, but the cut is curled upwardly where it presses through the grain surface at 37. The surface of the grain platform is skived off as indicated at 38 to provide a flesh surface for firm adhesion of top unit 39 to base unit 40.

Other variations of the methods and resulting products herein illustrated and described may be practiced while preserving the features which contribute to the ease or economy of manufacturing two-unit welting, or to the durable shape and lasting appearance of shoes made with such 60 welting.

I claim:

1. A method of making two-unit welting, which consists in dividing a grain leather fillet by forming an inclined cut in the flesh body of the fillet and a lateral cut adjacent its grain surface, the angle between said cuts being obtuse, thereby to provide a top unit having a grain deck, an undercut flesh wall and a grain lip projecting from the top of said wall, and a base unit 70 75

having a marginal flange of less thickness than the body of said unit, cementing the top unit to the base unit, and cementing said grain lip to said wall and to the top of said marginal flange as a cover flap therefor, thereby forming a receding welt shoulder and an inseam flange below said shoulder.

2. A method of making two-unit welting, which consists in dividing a grain leather fillet by forming an inclined cut in the flesh body of the fillet and a lateral cut adjacent its grain surface, the angle between said cuts being obtuse, thereby to provide a top unit having a grain deck, an undercut flesh wall and a grain lip projecting from the top of said wall, and a base unit 10 15 having a marginal flange of less thickness than the body of said unit, cementing the top unit to the base unit, and cementing said grain lip to said wall and to the top and outer edge of said marginal flange as a cover flap therefor, thereby forming a receding welt shoulder and a two-ply inseam flange below said shoulder.

3. A method of making two-unit welting, which consists in dividing a grain leather fillet by forming a short vertical cut in the base of the fillet, an inclined cut in the flesh body of the fillet and a lateral cut adjacent its grain surface, the angle between said inclined and lateral cuts being obtuse, thereby to provide a top unit having a grain deck, an undercut flesh wall and a grain lip projecting from the top of said wall, and a base unit 20 25 having a beveled marginal flange, cementing the top unit to the base unit, and cementing said grain lip to said wall and to the top of said flange as a cover flap therefor, thereby forming a receding welt shoulder and an inseam flange below said shoulder.

4. A method of making two-unit welting, which consists in dividing a grain leather fillet by forming a short vertical cut in the base of the fillet, an inclined cut in the flesh body of the fillet and a lateral cut inclining to its grain surface at the edge of the fillet, the angle between said inclined and lateral cuts being obtuse, thereby 30 35 to provide a top unit having a grain deck, an undercut flesh wall and a grain lip projecting from the top of said wall, and a base unit having a beveled marginal flange, cementing the top unit to the base unit, and cementing said grain lip to said wall and to the top and outer edge of said flange as a cover flap therefor, thereby forming a receding welt shoulder and a two-ply inseam flange below said shoulder.

5. A method of making two-unit welting, which consists in dividing a grain leather fillet by forming an inclined cut in the flesh body of the fillet, a lateral cut adjacent its grain surface, and a vertical cut through the grain surface remote from the edges of the fillet, the angle between said inclined and lateral cuts being obtuse, thereby to provide a top unit having a grain deck, and undercut flesh wall and a grain lip projecting from the top of said wall, and a base unit 40 45 having a marginal flange of less thickness than the body of said unit, inverting the base unit, cementing the top unit to the inverted base unit, and cementing said grain lip to said wall and to the top of the marginal flange of the inverted base as a cover flap therefor, thereby forming a receding welt shoulder and an inseam flange below said shoulder, the bottom of the flange being disposed in a plane appreciably above the plane of the bottom of said base unit.
